(57) **CLAIM**

The ornamental design for a zipper lock, as shown and described.

DESCRIPTION

FIG. 1 is a front isometric view of a new design for a zipper lock as described and claimed herein.

FIG. 2 is a rear isometric thereof.

FIG. 3 is a front view of the design of FIG. 1.

FIG. 4 is a rear view of the design of FIG. 1.

FIG. 5 is a left view of the design of FIG. 1.

FIG. 6 is a right view of the design of FIG. 1.

FIG. 7 is a top view of the design of FIG. 1.

FIG. 8 is a bottom view of the design of FIG. 1.

FIG. 9 is an exploded front perspective view thereof.

FIG. 10 is a top front isometric view of a new design for a zipper lock as described and claimed herein.

FIG. 11 is a rear isometric view of the design of FIG. 10.

FIG. 12 is a front view of the design of FIG. 10.

FIG. 13 is a rear view of the design of FIG. 10.

FIG. 14 is a left view of the design of FIG. 10.

FIG. 15 is a right view of the design of FIG. 10.

FIG. 16 is a top view of the design of FIG. 10.

FIG. 17 is a bottom view of the design of FIG. 10; and,

(Continued)

FIG. 18 is an exploded front perspective view of the design of FIG. 10.
